UNITED STATES PATENT OFFICE.

ROBERT RENTON HIND, OF HONOLULU, TERRITORY OF HAWAII.

ROTARY CUTTER.

1,273,488.

Specification of Letters Patent.

Patented July 23, 1918.

Application filed December 1, 1917. Serial No. 204,821.

To all whom it may concern:

Be it known that I, ROBERT RENTON HIND, a citizen of the United States, residing in the city and county of Honolulu, Territory of Hawaii, have invented certain new and useful Improvements in Rotary Cutters; and I do hereby declare the following to be a full, clear, and exact description of the invention, such as will enable others skilled in the art to which it appertains to make and use the same.

The invention relates to rotary cutters for comminuting cane, corn stalks and other vegetable matter, and has for its object to provide an apparatus of the kind described, in which the knives are so constructed and arranged as to materially reduce the liability of fracture, even when operating at high speeds, which will admit of the knives being spaced at any desired intervals upon the supporting shaft and of the individual knives being regularly spaced peripherally about the shaft, and the entire device assembled as a rigid structure, in which the liability of any of the parts working loose is practically eliminated, the whole constituting a simple, durable and efficient apparatus in which the individual parts may be readily replaced or interchanged.

In the accompanying drawings, Figure 1 is a vertical elevation, partly in section, of the improved cutter with the central portion thereof broken away.

Fig. 2 is a similar view showing a detail of the shaft construction.

Fig. 3 is a side elevation of one of the knives, and

Fig. 4 is an end view of the cutter.

Referring to the drawings, 1 indicates a shaft, preferably cylindrical, having near its ends journal sections 2, 2, and provided at its middle with a flange or collar 3, either formed integrally with the shaft or secured rigidly thereto, as by welding. To one end of the shaft is secured a coupling member 6 by means of which the shaft is secured to a suitable driving device.

Each of the knife elements consists of a body portion 10, provided with a central perforation 11 which closely embraces the shaft 1, said body portion being provided with opposite cutting edges 12, which are preferably disposed in curved relation to produce a draw cut, as said edges engage the cane or other material to be cut or comminuted. The knives are preferably made

of sheet steel and are of uniform thickness throughout, except at the cutting edges, which are necessarily beveled, which renders the individual knives of substantially uniform strength throughout and materially reduces the tendency of the knives to rupture, which is a common fault in similar devices in which the knives are attached to individual hub sections. As shown, each knife includes two oppositely disposed blade sections, but it will be understood that, if desired, each knife may include a larger number of radially disposed blade sections. Surrounding the central opening 11, in each knife, is a series of bolt holes 13, which afford means for locking the knives rigidly to the shaft 1, as will be hereinafter explained.

The knives are mounted in regular order longitudinally of the shaft so that the blades of successive knives are disposed in definite angular relation, as for example, at angular distances of 90° in the form shown, and between each successive pair of knives, there is disposed a distance piece or washer element 17, which is provided with perforations 18 which register with the perforations 13 in the individual knives and are adapted to receive through bolts 20, which latter also pass through registering openings 4 in the central collar or flange 3 rigid with the shaft, so that the bolts 20 serve to lock the knives and the distance pieces separating the same, rigidly to the shaft.

Against the outer face of each of the end knives, there is placed a removable washer or collar 15, which is similarly provided with openings registering with the openings 13 of the knives and 18 of the washers to receive the bolts 20, the ends of which bolts are threaded to receive suitable locking nuts 21. Each of the washers 15 is provided with a key way 19 to receive a key 16, which latter is provided with a curved edge to engage a registering key way 5 in the shaft so that when said keys 16 are driven in place, the knives are rigidly locked to the shaft by means of the keys 16 adjacent the ends of the series of knives and also by the engagement of the through bolts 20 with the rigid flange or collar 3.

In assembling the apparatus, the bolts 20 are passed through the holes 4 in the collar 3 and the knives and washers 17 are then threaded on the shaft and the bolts 20, in the relation shown in Fig. 1, one-half the number of knives and distance pieces or

washers being applied from each end of the shaft. When the appropriate number of knives and washers have been thus assembled, the end washers are applied and engaged with the bolts, after which the nuts 21 are set up to draw the knives and washers closely together longitudinally of the shaft. The keys 16 are then driven into place and after the coupling 6 is secured to the proper end of the shaft and the latter mounted in its bearings, the device is ready for operation. If it should be desired to space the knives at different distances longitudinally of the shaft, it is necessary only to substitute for the washers 17, other washers of appropriate thickness. It will be noted that the knives are interchangeable and should any one or more of them become damaged, it is only necessary to remove the knives and washers between the same and the ends of the shaft, after which the damaged knife may be removed and another substituted therefor, and the remaining knives of the series replaced.

In cutters of this general class, the very heavy side thrust due to the passage of the knives through the cane or other material to be cut, tends to break or rupture the knives at their point of juncture with the hub sections. The present construction, however, in which the knives are of uniform thickness and strength obviates this difficulty and practically eliminate any tendency of the knives to break under ordinary conditions of usage. The construction also admits of the knife shaft being directly connected to a high speed engine or motor, so that the knives may be driven at

a much higher rate of speed than has been permissible heretofore. The employment of the multiple through bolts to lock the knives to the shaft avoids the usual form of key seat in the shaft, which weakens the latter. The elimination of the key seat in the individual knives admits of the knives being used interchangeably and also avoids weakening the knives at the point where the usual key seat is formed. The rigidity of the whole structure, due to the locking of the knives and washers or distance pieces positively to the shaft greatly reduces the liability to breakage and absolutely prevents the knives working loose on the shaft.

What I claim is:—

1. A rotary cutter comprising a shaft, a fixed collar thereon, a series of knives having central perforations and engaging the shaft on each side of said fixed collar, spacing washers separating the knives, and bolts passing through registering openings in the fixed collar, the knives and the washers.
2. A rotary cutter comprising a shaft, a fixed collar and end collars thereon, a series of knives having central perforations engaging the shaft on each side of said fixed collar, spacing washers separating the knives, bolts passing through registering openings in the fixed collar, the end collars, the knives and the washers, and means rotatably connecting said shaft and the end collars yet permitting longitudinal movement of said collars on said shaft.

In testimony whereof I affix my signature.

ROBERT RENTON HIND.
